UNITED STATES PATENT OFFICE.

JOHN JOSEPH DUNWOODY, OF NEW YORK, N. Y.

COMBINATION IRONING-BOARD AND CHAIR.

1,333,392.

Specification of Letters Patent.

Patented Mar. 9, 1920.

Application filed October 25, 1919. Serial No. 333,214.

To all whom it may concern:

Be it known that I, JOHN JOSEPH DUNWOODY, a citizen of the United States, and a resident of the city of New York, borough 5 of the Bronx, in the county of Bronx and State of New York, have invented a new and useful Combination Ironing-Board and Chair, of which the following is a full, clear, and exact description.

- 10 This invention relates to a combined chair and ironing board, and has for an object to provide an improved construction wherein the back of the chair will act in the double capacity of a back and as a supporting leg. 15 Another object of the invention is to provide a chair with a folding back having an ironing board thereon, together with means which may be adjusted without the use of tools for converting the chair into a stand 20 for the ironing board.

In the accompanying drawing.

Figure 1 is a perspective view showing a chair and ironing board, disclosing an embodiment of the invention.

- 25 Fig. 2 is a vertical sectional view through Fig. 1 approximately on line 2—2.

- Fig. 3 is a view similar to Fig. 2, except 30 the parts are adjusted for converting the structure into an ironing board with the proper support therefor.

Fig. 4 is a detail fragmentary sectional view through Fig. 2 on line 4—4.

Referring to the accompanying drawing by numerals, 1 indicates the bottom of the 35 chair, said bottom being connected in any desired manner with the legs 2 and associated with the back 3 for completing the chair. It will be noted from the drawing that the bottom 1, legs 2 and back 3 form

40 the chair, while the board 4 forms the ironing board. The back 3 in addition acts as one of the supporting members associated with bottom 1 and legs 2 when the parts are arranged as shown in Fig. 3. In addition an auxiliary support 5 is provided which

45 acts in a certain sense as a cross brace. Back 3 consists of a pair of uprights 6 and 7 hinged at 8 and 9 to the rear legs 2, whereby they may swing to and from the position shown in Fig. 3. When in the position

50 shown in Fig. 1 clips 10 and 11 lock the back against accidental movement. These clips are provided with apertures through which short pins 12 extend, said pins being secured in any desired manner to the uprights 6 and

55 7. When it is desired to move the back 3

to the position shown in Fig. 3 the spring clips 10 and 11 are manually disengaged and the back swung over to the desired angle. Cross slats 13 and 14 are mortised into the 60 uprights 6 and 7, or rigidly secured thereto in some desired manner. A third or upper slat 15 is also provided, said upper slat being journaled in suitable apertures in the uprights 6 and 7 whereby it may freely rotate. 65 This upper slat is rigidly secured by nails, or otherwise, to the ironing board 4 near one end and turns therewith. The auxiliary brace 5 is pivotally mounted at 16 to the board 4, the pivotal connection being any 70 suitable form of hinge, as for instance a metal strip 17 embedded into the board 4 with upstanding ears through which journal pins extend, said pins extending into or through the brace 5. A pair of spaced 75 stops 18 and 19 are arranged on brace 5 so as to straddle the slat 13 when the parts are adjusted to be used as an ironing board and support. A clip or catch 20 is rigidly secured to the brace 5, said catch having an 80 aperture 21 which is adapted to snap over the pin 22 extending from the front of the seat 1.

When the parts are in the position shown in Figs. 1 and 2 an ordinary chair structure 85 is produced, while upon the releasing of the catches 10 and 11 the parts may be quickly adjusted for use as an ironing board, the back and brace 5, together with the bottom 1 and legs 2 acting as supports for the board. 90 It will be noted that there are no extra parts used to convert the device from a chair to an ironing board and support, or re-convert the ironing board and support into a chair. It will also be noted that the parts are adjustable manually without tools and when in either position is substantially locked so as to remain in the adjusted position until manually moved to some other position. 95

What I claim is:

1. A combined chair and ironing board comprising a chair body, a back hinged to the chair body, means for locking the back against accidental movement, an ironing board pivotally connected with said back adjacent one end, and means co-acting with the back for supporting the ironing board in a horizontal position when said support is in use. 105

2. A combined chair and ironing board comprising a chair body, an ironing board, a pivotally mounted member acting at one

100

110

time as a back to said chair body and at another time as a support for said ironing board, and a brace interlocking with said pivotally mounted member and said chair body for maintaining the ironing board in a horizontal position when in use.

3. A combined chair and ironing board comprising a chair body, an ironing board, a pivotally mounted member hinged to the 10 chair body and to the ironing board near one end, a bracing member hinged to said ironing board near the center, and means arranged at the opposite end of said bracing member to that adjacent the ironing board 15 for engaging the chair body when the pivotally mounted member has been swung to an angle to the vertical and the ironing board has been moved to a substantially horizontal position.
- 20 4. A combined chair and ironing board comprising a chair body, a pivotally mounted member hinged to the chair body and acting at one time as a back for the chair body and at another as a diagonal supporting 25 brace for the ironing board, a board hinged

to said pivotally mounted member, said pivotally mounted member having a bracing slat, a bracing member pivotally mounted on said board, and a pair of stops on the pivotally mounted member positioned to straddle said slat when the bracing member is acting as a support for said board.

5. A combined chair and ironing board and support comprising a chair body, an ironing board, a back structure pivotally 35 mounted on said chair body acting at one time as a back for said body and at another time as a support for the ironing board, catches for engaging said back for holding the same in one position when the device is 40 to be used as a chair, a pivotally mounted brace connected with the ironing board, means for connecting said brace with said pivotally mounted back when the back is acting as a support for said ironing board, 45 and a catch for connecting said members with said body for preventing accidental movement of the brace.

JOHN JOSEPH DUNWOODY.
